ABRASIVE CUTTING ROLL

Henry Marshall Field, Dayton, Ohio

Application April 2, 1947, Serial No. 738,821

4 Claims.

(Cl. 5—190)

1

This invention relates to abrasive cutting rolls and more particularly to formation of an abrasive roll formed of emery cloth or the like, wound with adhesive tape at one end for holding the blank in a roll.

It is an object of this invention to provide an abrasive cutting roll of the kind to be more specifically described hereinafter, which will possess a certain amount of rigidity, for cutting the work with which it is used, and yet possess a certain amount of flexibility, whereby the roll may be bent along its length for following the contour of the work piece. Heretofore, it has been the practice to apply glue to the smooth side of a blank of emery cloth or similar material, rolling the blank to the desired shape and permitting the glue to set for fastening the edge of the roll to the underlying layers of material. While this method has resulted in much success, the abrasive roll so formed has been quite rigid due to the inelasticity of the glued surfaces, where any bending of the roll resulted in cracking of the glue, separation of the glued surfaces, and immediate breakdown of the roll. Also, the glued surfaces of the abrasive roll when formed in this old manner, were required to be smooth, as the glue did not adhere well to the abrasive surface. This invention relates to an improved abrading roll, wherein a strip of adhesive tape, having an adhesive surface on both sides, is applied to an edge of a blank rolled to the desired shape, as a cylinder. In this manner, the tape may be applied equally as well to the rear or smooth surface, or to the front abrasive surface. The adhesive tape may be of the pressure type or hard drying type, and will be flexible so that the adhesive roll will have a certain degree of flexibility.

Another object of this invention is to provide an abrasive roll held in shape by a strip of adhesive tape, with adhesive on both sides, applied to one edge of a blank of material whereby the adhesive tape will be fixed to the overlying layers of the roll.

Still another object of this invention is to provide an abrasive roll held in shape by a strip of adhesive tape wound about one edge of the rolled material.

With the above and other objects in view, my invention consists in the arrangement, combination and details of construction disclosed in the drawings and specification, and then more particularly pointed out in the appended claims.

In the drawings,

Figure 1 is a side elevation, partly broken away, of an adhesive roll constructed according to an embodiment of this invention.

Figure 2 is an end elevation of the roll in Figure 1.

Figure 3 is a side elevation of a modified form of this invention.

Figure 4 is a vertical section taken on the line 4—4 of Figure 3.

2

Figure 5 is a longitudinal section taken on the line 5—5 of Figure 3.

Figure 6 is a side elevation, partly broken away, of a modified form of abrasive cutting roll wherein the abrasive surface is located on the inside of the cylindrical roll.

Figure 7 is an end elevation of the abrasive cutting roll shown in Figure 6.

Figure 8 is a side elevation, partly broken away, of a still further modification of this invention.

Figure 9 is a top plan view, partly broken away, of the blank having the adhesive tape fixed on the smooth surface of the strip of abrading material.

Figure 10 is a plan view, partly broken away of a blank showing the adhesive tape fixed on the abrasive surface.

Figure 11 is a plan view of a blank and adhesive tape which is used for securing the tape in the roll, as shown in Figures 3 and 8.

Figure 12 is a top plan view, partly broken away, of still another modification.

Figure 13 is a side elevation of this device.

Figure 14 is a fragmentary detail section of the interlocked roll, of Figures 12 and 13.

Referring to the drawings, the numeral 15 designates generally a blank or strip of material used in making abrasive cutting rolls. The strip of material may be emery cloth, which is most popular, having a smooth lower surface and a roughened or abrasive cutting surface on the opposite side. In forming these cutting rolls, it is customary to take a blank strip of material and roll it along its length to the contour desired for a particular job. It has been customary to provide glue of a hard setting type on the smooth surface of the abrasive material and rolling the blank to the desired shape. This method of forming a cutting roll results in a relatively brittle abrasive element. Upon flexing of the cutting roll, the glue will crack and the cutting roll will deteriorate very rapidly. By forming the abrasive cutting roll in the manner of this invention, the cutting roll or cylinder will be relatively rigid throughout its length and still maintain a certain degree of flexibility for following the contour of irregular or tubular work pieces.

For rolling the blank 15 and securing it in its rolled configuration, by this invention I provide 50 a strip of adhesive tape 16 which has adhesive material on both sides thereof, and apply the tape to one long edge of the blank. The blank 15 is substantially rectangular throughout its length as at 17, and is cut with a diagonal or inclined edge 18 at one end. The edge 18 is formed to be the outermost edge when the blank 15 is rolled, to provide a substantially spiral outer edge which is longer wearing and more suitably resistant to the cutting effect of the work on the cutting roll.

The adhesive tape 16 may be of the pressure type of tape which is fixed to the material by pressure and will remain fixed thereto. It may

be formed of other types of adhesive tape which will be suitably flexible so that the end of the roll or blank will be flexible at all times and overcome the brittle type of cutting rolls heretofore known.

In Figures 1 and 2 there is shown an abrasive cutting roll formed of a blank shown in Figure 9, with the abrasive surface 19 outermost and the adhesive tape 16 fixed or interposed between successive layers of the blank on the smooth side thereof.

In Figures 6 and 7 the adhesive tape 16 is fixed in the same way between successive layers of rolled blank 15 and the abrasive surface 19 is disposed inwardly, the roll 15 being formed of a hollow cylinder.

In Figure 10 the adhesive tape 16 is fixed initially to the abrasive side 19 of the blank 15 before the blank is rolled to the desired shape, and the abrasive cutting roll may be formed either as shown in Figures 1 and 2 for working radii or other surfaces, as on polishing moulds, forging dies, match plates, plastic moulds, die casting moulds, or for deburring applications, or may be rolled in the form of a cylinder, as shown in Figures 6 and 7 for working the surfaces of rods or other suitable work where the cutting roll may better do the job by encompassing the work.

In Figures 3 and 8 the abrasive blank 15 is initially rolled to the desired shape of a solid cylinder or hollow cylinder, and the tape 16 is wound about one end of the roll when it is completed. Instead of being interposed between the successive layers of the blank, the tape 16 is wound completely about the edge of the roll after the roll has been formed. This type of application of the tape 16 to the cutting roll may be used with the abrasive surface 19 outermost, as shown in Figures 3 to 5, or innermost as shown in Figure 8.

The tape 16, as shown in Figures 4 and 5 is wound about the blank 15 one complete turn, but may be wound about any number of times to provide a shank on the abrasive cutting roll for insertion of a chuck of a tool with which the cutting roll is used.

In the types of cutting rolls wherein the abrasive surface is disposed inwardly of the hollow cylinder, the diagonal edge 18 which forms a sharp spiral will be disposed inwardly also on the abrasive surface. The sharp spiral of the edge 18 as stated before, is more suited for an abrasive roll of this kind than a straight edge on the cutting surface in that the entire edge is not exposed to the work at one time. In a revolution of the cutting roll, points along the edge 18 come into contact with the work successively as the work is rotated.

Referring now to Figures 12 to 14, there is shown a form of this abrasive roll, having an adhesive material along one longitudinal edge and so formed that that edge when the blank 20 is rolled will be interlocked with the adjacent overlying edge. The abrasive strip 20, similar to the abrasive strips described above, is formed with an abrasive surface 21 on one side thereof and a smooth surface 22 on the other side. The adhesive material 24 is fixed to one longitudinal edge of the blank 20 before the blank is rolled to the desired shape.

A series of tangs 25 are struck from the edge of the blank upon which the adhesive material is fixed, leaving points 26 below each tang. The tangs 25 are preferably V-shaped and longitudinally spaced apart, forming a longitudinal series of tangs 25 and correlated openings 26.

When the blank 20 is rolled upon itself to form the completed abrasive roll, the tangs 25 of the lowermost layers are adapted to extend through the openings 26 of the overlying layer, 5 for interlocking the adjacent layers of the completed roll. The interlocked edges of such an abrasive roll will provide for the more secure adhesion of the overlapping layers during the use of the roll while permitting a certain degree of 10 flexibility of the completed cartridge.

In the use of this type of abrasive roll, speeds of from 40,000 to 75,000 R. P. M. are frequently attained. The interlocking or interengaging 15 tangs assist the adhesive tape or other adhesive material in holding the roll together at such speeds.

I do not mean to confine myself to the exact details of construction herein disclosed, but claim all variations falling within the purview of the 20 appended claims.

What I claim is:

1. An abrasive roll comprising an elongated blank, flexible material having an abrasive surface and a smooth surface, adhesive material 25 along the longer longitudinal edge of said blank, said blank being rolled upon itself to form a cylindrical body, said one longitudinal edge having V-shape tangs struck therefrom providing a series of V-shaped openings, said tangs engageable through said openings in the overlying layer of said body for interlocking the successive layers of said roll.

2. An abrasive roll comprising an elongated blank of flexible material having a smooth surface and an abrasive surface, adhesive along one longitudinal edge of said blank, tangs struck from said blank along said one adhesive edge forming a series of openings adjacent each tang, said blank rolled upon itself to form a cylinder, said 35 tangs engageable through openings of overlying layers of said roll for interlockingly securing the edges of successive layers of said roll.

3. An abrasive roll comprising an elongated blank of flexible material, tangs struck from said 45 blank along one longitudinal edge forming a series of openings, said blank being rolled upon itself to form a cylinder, said tangs engageable through opening of overlying layers of said roll for interlockingly securing the edges of successive layers of said roll.

4. An abrasive roll comprising an elongated blank of flexible material, tangs struck from said blank along the length thereof forming a series of openings, said blank being rolled upon itself to form a cylinder, said tangs engageable through 55 openings of overlying layers of said roll interlockingly securing successive layers of said roll together.

HENRY MARSHALL FIELD.
